[57] ABSTRACT

A spring-fastener for interconnecting layers of tent cloth and the like comprises two equal-sized resilient fastening heads which are fixedly interconnected and which project in opposite directions, there being an anchoring portion between said heads, each of which heads, at opposite sides of said anchoring portion, extending from a neck of smaller diameter than the largest diameter of the heads for selective and releaseable connection by either of said fastening heads onto an annular securing member or eyelet secured to the layer of cloth.

FASTENING DEVICE

BACKGROUND OF THE INVENTION

1. Field of the Invention

This invention relates to a spring-fastener of molded plastic material which is receptive in grommets or eyelets carried by a canvas type of cloth.

2. Prior Art

For interconnection of the borders of two overlapping layers of tent cloth, such borders have previously been provided with ordinary elongated buttonholes, and at each buttonhole a double button has been provided, said button having two interconnected rigid button discs so as to optionally permit overlapping of the upper side or lower side of one cloth by the second cloth. It has, however, turned out that the buttoning of the layers of tent cloth by such double buttons is troublesome owing to the difficulty in manipulating the button through the button hole due to the fact that the button must be placed on its edge or in an inclined position in relation to the cloth and this placing is rendered difficult by the construction of the double button with the two button discs, particularly with regard to the relatively rigid material of tent cloth and the like.

SUMMARY OF THE INVENTION

The new spring-fastener comprises two equal and resilient fastening heads which are fixedly interconnected and project in opposite directions, the spring-fastener having an anchoring portion positioned half-way between said heads each of which at opposite sides of said portion extend from a neck with smaller diameter than the largest diameter of the heads for optional and releasable connection by any of the fastening heads to an annular securing member. When interconnecting the layers of cloth in overlapping position by this new spring-fastener, it is only necessary to exert an axial pressure on one of the said heads to cause the second resilient head to project through, and by its resilient property, to engage with said annular member. This construction facilitates the interconnection of the layers of cloth by the fact that the common axial line of the two heads during the entire assembling may retain its perpendicular position in relation to the planes of the two layers of cloth which are permitted to overlap each other in the manner desired.

The invention has for its object to eliminate these difficulties, the subject matter of the invention being a spring-fastener which particularly but not exclusively is intended to be used for said purpose.

The invention also has for its object to provide a spring-fastener for said purpose which is simple in construction, efficient in operation and cheap in manufacturing.

The invention is made more clear by the following description with reference to the accompanying drawings showing some embodiments of the invention and in which:

ON THE DRAWINGS

FIG. 1 shows an axial section of one half of the spring-fastener;

FIG. 2 shows an endview of the same;

FIG. 3 shows an axial section of a spring-fastener composed of two halves thereof shown in FIGS. 1 and 2 interconnecting two layers of cloth or portions of a layer of cloth;

FIG. 4 is a side-elevation of a second embodiment of the spring-fastener;

FIG. 5 is an axial section of the spring-fastener of FIG. 4 inserted and anchored in an annular securing or anchoring member or eyelet;

FIG. 6 is a plan view of the border portion of a cloth with a spring fastener according to FIGS. 4 and 5 inserted and anchored in an eyelet secured to the edges of a hole in the cloth, said portion having a second eyelet without any spring-fastener inserted therein;

FIG. 7 is an axial section of a spring-fastener according to a third embodiment;

FIG. 8 is a view corresponding to FIG. 6 and showing a spring-fastener according to FIG. 7 inserted in one of two eyelets;

FIGS. 9 and 10 are sectional views illustrating the manner of connecting this third embodiment with an anchoring eyelet;

FIGS. 11 and 12 are a side elevation and an endview respectively of a spring-fastener according to a fourth embodiment; and

FIG. 13 is a side elevation of a fifth embodiment.

AS SHOWN ON THE DRAWINGS

25 The first embodiment, illustrated in FIGS. 1 and 3, comprises two hollow heads 10 of the spring-fastener, said heads having a circular cross-sectional shape and projecting each from a base plate 11. The heads 10 have slots 12 disposed in axial planes and merge in the 30 base plate via a neck portion formed by a peripheral or circumferential groove 13. According to FIGS. 1 and 3, the slots 12 are four in number and, since the fastener is made from a resilient material, preferably plastic, the portions 14 between the slots form tongues which are in radial direction resiliently bendable inwardly towards the axial centerline of the head from the position shown in the drawings. The base plate 11 has a central hole 15 and a peripheral or circumferential groove 16, the bottom of which in axial section 35 forms an arc such as a quadrant.

Two parts of the form shown by FIGS. 1 and 2 are combined with the bases 11 bearing against each other so that the two baseplates form the anchoring portion of the fastener and may be connected onto an annular securing member, grommet or eyelet 18 made, for example, from brass or other suitable metal. In order to constitute the spring-fastener, the base plates of said two parts are interconnected by securing means such as a rivet 19 through the holes 15. In mounted position of the spring-fastener, the grooves 16 from each side engage with the eyelet 18. This connection of the fastener with the cloth 17 is provided to be permanent. The spring-fastener may then be easily and optionally connected with a second annular securing member or eyelet 20 in a second cloth 21. The interconnection of the layers of cloth is effected by inserting the head in question against the spring action of the tongues 14 in the second eyelet 20, which has the same size and form as the first eyelet 18. When this displacement of the fastener has been executed until the eyelet 20 engages the neck 13, the releasable connection between the two cloths 17 and 21 is attained. The connection may be released by an axial pressure against the head 10 engaging with the eyelet 20.

According to FIG. 3 the border portion of the cloth 17 with the fastener permanently connected therewith is kept over the border portion of the second cloth 21,

but owing to the fact that the fastener has two heads 10 the fastener may be used in a quite analogous manner when the border of the cloth 17 is to be kept under the border of the cloth 21.

In the embodiment according to FIG. 4 to 6, the heads 10 of the spring-fastener constitute integral portions of the same body made from resilient material such as suitable plastic, said body being hollow and broadly speaking cylindrical. The axial middle portion of this body is externally provided with a peripheral or circumferential groove 16 extending all round the body, and both heads have axially disposed slots 12 in suitable member, according to the drawings three slots in each head, and positioned mutually at equal angular distances. The slots of the one head are angularly displaced in relation to the slots of the second head and extend along more than half the axial length of the cylindrical plastic body. Owing to this fact not only the tongues 14 of the heads but also the middle or anchoring portion of the body will be resilient in radial direction so that said portion with utilization of the resilient of the fastener may be pushed into the substantially rigid eyelet 18 serving as an attachment for the spring-fastener. In order to secure the inserted fastener in its position, it is formed with an internal offset or flange 22 which is so positioned that a plug 23 can be pressed into the cylindrical inner space of the fastener and bear against the flange 22. the plug thus secured in the fastener is positioned radially inside the groove 16 or the eyelet 18 respectively and prevents inward yielding of the anchoring portion of the fastener. The plug is held in position due to the resiliency of the material but may, if desired, be fixed by glue or other fastening means in its position.

The embodiment shown in FIGS. 7 and 8 differs from the one just described in that the middle or anchoring portion of the hollow fastener is substantially non-resilient by the provision of a partition halfway between the fastener heads, said partition being formed integrally with the fastener. As shown by FIG. 9, the opening of the eyelet 18 prior to the fastening procedure is great enough for narrowly inserting the fastener into it so that its groove 16 will be located inside said groove. Then the eyelet is compressed, crimped or flattened by the aid of a suitable tool in such a manner that the inner diameter is sufficiently reduced so as to clamp the fastener in its position in the groove 16 as shown by FIG. 10.

The embodiment shown in FIGS. 11 and 12 differs from the embodiment described substantially in that each head 10 of the spring-fastener has one slot 12 only and is divided in two resilient tongues 14 widening towards the inner end. By this design a particularly solid and durable spring-fastener is obtained.

The embodiment shown in FIG. 13 is made in one piece forming a body of a softer and more resilient material than that of the embodiments described, said material being by preference a rubberlike plastic. Said body may be solid and have the shape of a solid of revolution. Like the other embodiments and body has two fastener heads projecting each in opposite axial directions from a corresponding neck 13. At the middle of its axial length said body has a substantially cylindrical anchoring portion with somewhat longer diameter than that of the necks 13 and forming the bottom of the circumferential groove 16 for the reception of the annular securing member or eyelet 18. In the axial direction of

the body said groove 16 is limited by two spaced flanges 25, each of which by a frusto-conical portion 26 merging in the adjacent neck 13. When the fastener or body is to be mounted in its annular securing member 18, the one or the other head 10 and the adjacent flange 25 is pushed through said securing member 18 in which operation a certain axial pressure is required for elastic deformation of the head and a higher pressure is required for bending said flange enough to push it through the securing member 18. This bending of the flange 25 is facilitated by the edge-action exerted by the conical surface 26 in co-operation with the securing member 18 which may be of a substantially rigid material, preferably metal. When the flange has passed through the securing member 18, the flange 25 resumes its position shown in the drawing, in which the annular member 18 is locked between side surfaces 27 of the flanges 25, said side surfaces facing toward one another and being substantially perpendicular to the axis of the body or possibly having a slightly concave shape.

A suitable material for the spring-fastener according to the embodiments shown in FIGS. 1-12 may be a plastic having the trademark DELRIN, or a suitable metal. For the embodiment according to FIG. 13 a plastic material with the trademark DESMOPAN may be used. In both cases, other suitable plastic materials may be used.

The invention is not restricted to the embodiments shown in the drawings. For example, as shown, the number of the slots in the fastener heads may be varied, and the heads may have shapes equivalent to those shown in the drawings.

I claim as my invention:

1. A spring fastener for permanent connection to a first substantially rigid annular securing member carried by a first layer of fabric and for detachable connection with a second substantially rigid annular securing member of the same internal size carried by a second layer of fabric and to be disposed at either side of said first layer, said spring fastener comprising:

a. a pair of resilient heads of equal size projecting in opposite directions, and each having a circumferential groove defined at one side by an axially outer flange and at the other side by an inner flange to form a neck in the groove having a diameter smaller than said flanges, the groove of each of said heads being receptive of said second annular securing member to enable said head to project therethrough for access; and

b. an anchoring portion fixedly interconnecting said inner flanges and having a circumferential groove therebetween defined by said inner flanges to form a third neck at the axial center of the fastener receptive of said first annular securing member, said anchoring portion being less resilient than said heads and having a maximum diameter no greater than said inner flanges.

2. A spring fastener according to claim 1 in which both of said inner flanges will permit said first annular securing member to pass thereover for the reception of said first annular securing member around said third neck.

3. A spring fastener according to claim 1 in which all of said flanges are of the same diameter.

4. A spring fastener according to claim 1 in which said inner flanges have a diameter greater than said outer flanges.

5. A spring fastener according to claim 1 in which the sides of said inner flanges which face each other are substantially perpendicular to the longitudinal axis of the fastener and their other sides are frustoconical and respectively merge into the adjacent neck.

6. A spring fastener according to claim 1 in which said heads are hollow and said anchoring portion is substantially solid.

7. A spring fastener according to claim 6 in which said anchoring portion includes an annular flange axially offset from the center, and a separate plug axially aligned with the groove in said anchoring portion.

8. A spring fastener according to claim 1 in which each said head and one-half of said anchoring portion comprise two equal separate parts, said heads being hollow and slotted, the anchoring portions being apertured, and a securing member insertable through either head and extending through said apertures for access by a locking tool.

9. A spring fastener as claimed in claim 1, the fastener having the shape of a solid of revolution, said inner flanges being elastic and the sides of said flanges facing in opposite axial directions being conical and tapering each to the adjacent neck, and the sides of the flanges facing toward one another being substantially perpendicular to the axis of the solid of revolution.

10. A spring-fastener as claimed in claim 1 having securing means, each of the fastening heads via its neck

merging in a plate and the two plates of the fastening heads each having a central hole for said securing means so as to form together said anchoring portion.

11. A spring-fastener as claimed in claim 1, the spring-fastener being hollow, each fastening head having at least one axial slot and the position of the slot of the one head being angularly displaced in relation to the slot of the second head.

12. A spring-fastener as claimed in claim 1, the slots of the heads extending through more than half the axial length of the spring-fastener.

13. A spring-fastener as claimed in claim 12 including a plug insertable in the hollow spring-fastener for preventing inward springing of the anchoring portion, and for locking the spring-fastener to the annular securing member after its insertion into said annular member.

14. A spring-fastener as claimed in claim 1, the anchoring portion of the spring-fastener being substantially non-resilient for receiving a second member comprising deformable material so that the inner diameter of said second member, after insertion of the spring-fastener therein, is reducible, into said peripheral groove in said anchoring portion.

15. A spring fastener as claimed in claim 1, each head having an axial slot widening toward said anchoring portion.
